United States Patent Office

Des. 218,816
Patented Sept. 29, 1970

218,816

CHAIR

Gardner Leaver, New York, N.Y., assignor to Steelcase Inc., Grand Rapids, Mich., a corporation of Michigan
Continuation-in-part of design application Ser. No. 14,253, Oct. 31, 1968. This application Mar. 20, 1969, Ser. No. 16,351

Term of patent 14 years

Int. Cl. D6—01

U.S. Cl. D15—1

FIG. 4.

FIG. 5.

FIG. 6.

FIG. 1 is a slightly elevated perspective view of a chair showing my design;

FIG. 2 is a front perspective view of the chair;

FIG. 3 is a side elevational view of the chair;

FIG. 4 is a rear perspective view of the chair;

FIG. 5 is a lower perspective view of the chair; and

FIG. 6 is a modified form of the chair of FIG. 1 wherein a webbed seat and backrest member is employed in lieu of the unitized cushion.

This application is a continuation-in-part of the application for chair design, Ser. No. 14,253 filed on Oct. 31, 1968, and now abandoned.

I claim:

The ornamental design for a chair, substantially as shown and described.
